UNITED STATES PATENT OFFICE

ROBERT HEAD, OF NEW YORK, N. Y., ASSIGNOR TO THE AEOLIAN COMPANY, A CORPORATION OF CONNECTICUT.

SOUND-BOX.

1,278,341.

Specification of Letters Patent. Patented Sept. 10, 1918.

Application filed August 9, 1917. Serial No. 185,313.

To all whom it may concern:

Be it known that I, ROBERT HEAD, a citizen of the United States, residing at New York, in the county of New York and State of New York, have invented new and useful Improvements in Sound-Boxes, of which the following is a specification.

The present invention relates to sound-boxes for phonographs, and more particularly to the vibrating stylus-carrying element thereof. It comprehends certain hereinafter-described improvements in the mounting of the aforesaid element, which is commonly termed the stylus bar, whereby said bar may be readily and quickly applied to a sound-box and, in the event of injury, removed therefrom, and whereby, when in place, it will be held against all rattling, while at the same time possessing the required site freedom of movement.

According to the invention, the sound-box is provided, as usual, with a pair of spaced supporting parts wherein the stylus bar has a rocking mounting; but instead of both of these parts or lugs supporting the bar to an equal extent, as is ordinarily the case, one of them is furnished with a small leaf spring, which provides the required bearing at that side of the bar, and which presses said bar toward the other lug. The spring extends over a cut-away portion of its carrier lug, and in that way can be forced back toward the wall of such portion when it becomes necessary to either insert or remove the bar.

An embodiment of the invention is illustrated in the accompanying drawing, wherein:

Figure 1 is a face view of a sound-box equipped with the improved stylus bar mounting.

Fig. 2 is an edge view thereof.

Fig. 3 is a view similar to Fig. 2, but showing the bar in the act of being attached to the sound-box.

Fig. 4 is a sectional view, taken on line 4-4 of Fig. 1, showing the mounting of the spring.

Fig. 5 is a view similar to Fig. 2, but showing a modification or development of the invention.

Referring more particularly to said drawing, the sound-box 7, which may be of any preferred construction, is provided with a pair of spaced projections or lugs 9 and 9^a,

these lugs being formed integrally with, or otherwise rigidly connected to, the body 8 of the sound-box at the lower part thereof. The aforesaid lugs are utilized to support the stylus bar, and in the more usual construction they are provided with openings to receive the ends of a fulcrum 10 carried by the bar.

In the present construction, the lugs are made long enough to extend forwardly across the rim 10 of the sound-box, and only one of them is provided with a bearing. The latter, which is indicated at 11, is located in the inner face of the lug, and has the form of a cone-shaped depression or seat. A portion of the inner face of the other lug 9^a is cut away, thus producing a clearance space 12 between the wall of the cutaway part and a small leaf spring 13, the rear end of which latter is fastened by a rivet 14, or the like, to the face of the shoulder 15 formed consequent upon the provision of the said clearance space. The spring is thus free to move backward and forward in the clearance space to permit manipulation of the stylus bar 16 incidental to attachment and removal thereof, as subsequently explained, the outer portion of the spring being provided with an opening 17 which is located directly opposite the seat 11.

The stylus bar 16 is, or may be, in the main of conventional form, and it is fastened at its upper end to the diaphragm 18 in the usual manner, its lower portion 19 being enlarged or thickened longitudinally and socketed at the terminal thereof to receive the stylus 20, which is held in place by the clamping screw 21. In the construction illustrated, which may be regarded for all practical purposes as preferred, the aforesaid thickened part 19 is formed with a pivot comprising two bearing pins 22 that project laterally outward from its opposite side faces. These pins 22 are, of course, disposed in axial alinement, and they are provided at their outer ends with conical points 23, one of which is designed to seat in the depression 11 in the upper lug or bearing part 9, and the other in opening 17 in the spring 13, the two lugs or bearing parts 9 and 9^a, being positioned with that end in view. The engagement of the bearing points 23 of the pins 22 in their respective seats 11 and 17 can readily be effected, because the spring 13 yields during this operation, moving 110

backward into the clearance space 12 so as to permit the centering of the upper point, as shown in Fig. 3.

At the conclusion of the centering operation, the pressure upon the spring is removed, and the latter then acts to hold the stylus bar sufficiently firm to prevent side-wise movement or rattling, while at the same time permitting it to vibrate about its pivotal axis with the requisite freedom, the connection of the upper end of the bar to the diaphragm being effected subsequently to its above-described attachment to the supporting lugs, as will be understood.

15 In order to avoid accidental displacement of the stylus bar, due to disengagement of the spring 13 from the adjacent bearing pin 22, there may be employed a guard which acts to preclude backward movement of said 20 spring to an extent sufficient to permit such disengagement. This guard preferably consists of a small, pin-like member 24, which is mounted for endwise movement in a hole drilled therefor through the spring-carrying 25 lug 9^a, the arrangement enabling the pin to be retracted just before the attachment of the bar takes place, and to be thereafter advanced through said hole until its inner 30 end almost, but not quite, touches the under side of the spring. The member in question may, if desired, be threaded, in which case its outer end will be enlarged to form a head and the wall of the hole in which it fits will likewise be threaded, all as represented in Fig. 5.

Referring again to the lug 9^a, this has a number of functions. For example it protects the spring 13 from possible injury in handling the box. Also it is adapted as to 40 its distance from the spring so that the latter cannot be over-bent when inserting the stylus-bar. This is of importance in itself as well as from a manufacturing standpoint,—because it makes it practical to manufacture sound-boxes in quantities which will be all alike with substantially uniform stylus-bar tension; and to do this without 45 adjusting the tension in the individual boxes.

I claim as my invention:—

50 1. A sound-box, having a pair of spaced supporting parts thereon, one provided with a seat; a spring secured to the other part and having a seat at its free end alining with the first-named seat; and a stylus bar provided

with a pivot pin which is disposed between 55 said supporting parts and has its terminals removably engaged in said seats; the spring-carrying part being spaced a short distance from the free end of said spring to prevent the spring from being overbent during the 60 engagement and disengagement of said pin.

2. A sound-box, having a stylus bar which is mounted thereon for vibratory movement; said bar having a rigid bearing at one end of its axis of vibration, and a yielding bearing 65 at the other end thereof; and means acting to normally prevent the second-named bearing from excess yielding.

3. A sound-box, having a stylus bar which is mounted thereon for vibratory movement; 70 said bar having a rigid bearing at one end of its axis of vibration, and a yielding bearing at the other end thereof; and a guard movable into and out of position to prevent the second-named bearing from excess yielding. 75

4. A sound-box, having a pair of spaced supporting parts thereon, one provided with a seat and the other with a yieldable spring having a seat alining with the first-named seat; a stylus bar having a transverse pivot 80 member whose terminals are removably engaged in said seats; and means arranged on the spring-carrying supporting part for normally preventing said spring from excess yielding. 85

5. A sound-box having a pair of spaced supporting parts thereon, one provided with a seat and the other with a yieldable spring having a seat alining with the first-named seat; a stylus bar having a transverse pivot 90 member whose terminals are removably engaged in said seats; and a member carried by the second-named bearing part for movement endwise into and out of position to prevent said spring from excess yielding, 95 thereby to hold said pivot member in such engagement.

6. A sound-box, having a pair of lugs thereon; a spring carried by one of said lugs; and a stylus bar removably supported 100 intermediate its ends between said spring and the other lug; the spring having its free end normally spaced from its carrier lug, whereby it is prevented from over-bending during the insertion of the stylus bar. 105

In testimony whereof I have hereunto set my hand.

ROBERT HEAD.
